FLUID CONTAINER

Paul A. Westphal, Los Angeles, Calif.

Application October 3, 1932. Serial No. 636,036

2 Claims. (Cl. 120—65)

My invention relates to fluid containers, and more particularly to such containers which are of simple construction, attractive in appearance, especially adaptable to be used as an ink-well, having a plurality of fluid receptacles arranged in pairs, comprising the receiving and the storing tanks or receptacles, adapted to hold therein the writing fluid, having each pair of said receptacles provided with fluid passages, so that spilling or drying of the said writing fluid may be entirely eliminated.

It accordingly is an object of my invention to provide said container with a plurality of fluid receiving and storing tanks, having the fluid passages arranged in such a manner whereby the fluid level may be maintained at all times, and whereby the used portion of the said fluid may be replenished automatically.

A further object of my invention is to provide the said receiving tank with a valve, which will prevent the fluid evaporation, having a cap and a wiper associated therewith, so that when in use, said wiper will clean the pen upon which the surplus ink matter may be accumulated, yet, the said pen will carry sufficient amount of the writing fluid necessary for the user.

Further objects and advantages of my invention, as will hereinafter more fully appear, I attain by the construction described in the specification and illustrated on the drawings, forming a part of my application.

Reference is had to the accompanying drawings, in which the reference characters denote the similar parts.

35 In the drawings;

Fig. 1 is the perspective view of the fluid container.

Fig. 2 is the side elevational view thereof.

Fig. 3 is the cross-sectional view of the fluid container, taken in the direction of the arrow 40 3—3, of the Fig. 2.

Fig. 4 is an enlarged cross-sectional view of the closing cap, taken in the direction of the arrow 4—4, of the Fig. 3.

Fig. 5 is an enlarged cross-sectional view of the receiving tank showing the controlling valve in position, taken on the line 5—5, of the Fig. 3.

Fig. 6 is the cross-sectional view of the dip cup, taken on the line 6—6, of the Fig. 2.

Fig. 7 is the transverse cross-sectional view of the fluid container taken in the direction of the arrows 7—7, of the Fig. 3.

Fig. 8 is the perspective view of the fluid container, in modified form.

55 Fig. 9 is the top view thereof.

Fig. 10 is the longitudinal cross-sectional view taken on the line 10—10, of the Fig. 9.

Fig. 11 is an enlarged cross-sectional view of the dip cup taken on the line 11—11, of the Fig. 10.

Fig. 12 is the cross-sectional view of the cup, 60 taken on the line 12—12, of the Fig. 11.

Fig. 13 is the cross-sectional view of the locking means of the cup, taken on the line 13—13, of the Fig. 11.

Fig. 14 is the top view of the closing cap, of said 65 cup.

Describing my invention more in detail, said invention comprises a body, generally designated by numeral 2, which may be of any preferred design, having a base 4, as shown.

Said body 2 is provided with a plurality of 70 fluid containers or tanks 6, adapted to hold therein the writing fluid which may be of various colors, if it is so desired, which are made of non-corrosive material such as glass or the like, 75

having a passage 8, extending into the receiving tank 10, and having a valve positioned therein, the purpose of which will be presently described.

The top of the body structure 2 is provided 80 with a removable cap 12, threaded as at 14, having a recess 16, enclosing a plurality of closing plugs 18, which are adapted to close the said fluid tanks 6, thus preventing an accidental out-flow of the fluid from the said tanks.

The base 4 is provided with a plurality of caps 85 20, which may be of any preferred configuration, having an opening as at 22, through which said fluid from said receiving tank 10 may be drawn, and which is also for the purpose of holding in 90 place a wiper member 24, as shown in Fig. 6.

The writing fluid is poured into the container 6, through the plug 18, which flows through the passage 8, into the receiving tank 10; the said passage 8 is held open by means of a rod 95 26, of which one end is located within the plug 18 as at 28, and the other end pressing against the valve plate 30, which is supported and held in place by means of a spring 32, as shown in Fig. 5.

The fluid within the said tank 10 may be removed through the dip cup 34, which comprises a perforated drum 36, having an upward ridge as at 38, adapted to receive a packing 40, said ridge extending downwardly as at 42 to receive 105 a spring 44, which is for the purpose of holding said drum 36 in position, thus preventing spilling of said fluid from said tank 10.

For the purpose of assembly, I have provided the bottom section of said tank 10 with a plug 110

50, which may be screwed in place as at 52 and adapted to hold the said spring 44, in place as shown, and the top of the said drum 36, is being provided with a ring 46 which is for the purpose of preventing the said drum 36 from being pushed into said tank 10.

5 In the Fig. 8 I have shown the fluid container in modified form, wherein the body 2' comprises a storing tank 6' and the receiving tank 10', respectively, having a plurality of passages 54, leading into the ink well tank 56, wherefrom the writing fluid may be drawn.

10 Said storing tank 6' is provided with a plug 18' which is adapted to be screwed in place as at 58, having a rod 26' positioned as at 28', extending downwardly into said receiving tank 10' and adapted to press against the valve plate 30' which is supported and held in place by means of a spring 32', as shown.

15 20 The body 2', storing tank 6' and the receiving tank 10', may be made, if so desired, out of suitable material such as glass or the like, having the side extensions 62, designed to meet the requirement of general use and purpose, also having the said tank 10' and the ink well tank 56, enclosed with a plate 64 and 66 respectively, which may be cemented in place as at 68, (see Fig. 11).

25 30 The dip cup 34' comprises a guard 70, which is perforated as at 72 and provided with a plurality of guides 74, for the purpose of guiding and to prevent turning of the perforated drum 36', which is also provided with a guiding ring 76, adapted to receive the said guides 74 and having the packing 40' positioned as at 78, bearing against the shoulder 80 of the said guard 70, (see Fig. 11).

35 40 The bottom section 82 of the said drum 36' is cone shaped and extends downwardly into the well tank 56, which is for the purpose of receiving and holding a limited amount of writing fluid at all times, and the top section 84 of the said drum 36' is entirely enclosed, (see Figs. 11 and 13) having an opening 86 positioned as shown through which the fluid may be drawn as needed.

45 50 The external surface of the said top section 84 is provided with a plurality of threaded sections 88, which are adapted to be received by the threaded sections 90 of the said cap member 20'.

55 The drum member 36' is being held in place by means of the spring 44', thus having the threaded sections 88 and 90 always in position,

so that, by turning the cap 20', said threaded sections 88 and 90 will interlock, drawing the drum 36' upwardly, bearing against the packing 40', thus closing the said well 56, preventing the evaporation of the fluid.

50 55 In operation the fluid within the said tank 10 is always held at the level, which corresponds to the position of the passage 8, within the said tank 10, and when the said drum 36 is pressed into said tank 10, it is held in place by means of the collar 46, thus allowing the fluid to flow through the openings 48, so that only a limited amount of fluid may be drawn from the tank 10, at one time.

60 65 In the event it is desired to fill a fountain pen with said writing fluid, the said fluid is being drawn from the tank 10 through the dip cup 34, and to prevent an excess accumulation of the fluid matter around the pen or pen-holder, the wiper 24 eradicates all of the surplus matter so collected upon its surface.

70 75 While I have thus described my invention with great particularity, it will be clear that the same may be modified throughout a wide range; I accordingly do not propose to be limited to the exact details of construction shown and described, but reserve the rights in practice to make modifications, which may come within the scope of the appended claims.

I claim as my invention:

105 1. In the apparatus of the class described comprising a container and a tank, a neck member connecting the said container and the said tank forming a passage, a cap detachably associated with said container having a recess, a valve plate 110 supported by a resilient means enclosing said passage of said neck and a rod associated with said valve plate and said recess in the cap, adapted to operate the said valve within said tank.

110 115 2. In a pen dip well having an opening, a movable dip cup for said opening having perforations in the side wall thereof, an upwardly extending ridge surrounding the base of the dip cup forming a recess, a packing positioned within said recess for tightly engaging the edges of 120 the well opening acting as a valve, a spring mounted on the bottom of the dip well acting against the bottom of the dip cup to hold the valve portion closed and a collar at the top of said drum to limit downward movement of the 125 cup so as to allow a limited amount of fluid to flow into the dip cup.
